Patented June 26, 1962

193,111

COMBINED FISH AND DEPTH FINDER

Thomas F. Sarah, 848 Valdes Ave., Akron, Ohio

Filed Aug. 23, 1961, Ser. No. 66,465

Term of patent 14 years

(Cl. D52—6)

FIG. 1 is a side elevation of a combined fish and depth finder embodying my new design.

FIG. 2 is a front elevation thereof.

FIG. 3 is a top plan view thereof.

FIG. 4 is a bottom plan view thereof.

I claim:

The ornamental design for a combined fish and depth finder substantially as shown.
